UNITED STATES PATENT OFFICE.

HERBERT L. MEEDER, OF DENVER, COLORADO, ASSIGNOR OF ONE-HALF TO ALLISON STOCKER, OF DENVER, COLORADO.

INTERNAL-COMBUSTION ENGINE.

1,206,016.

Specification of Letters Patent. Patented Nov. 28, 1916.

Application filed September 14, 1915. Serial No. 50,567.

To all whom it may concern:

Be it known that I, HERBERT L. MEEDER, a citizen of the United States, residing in the city and county of Denver and State of Colorado, have invented certain new and useful Improvements in Internal-Combustion Engines; and I do declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to improvements in internal combustion or explosive engines, my object being to provide a construction of this character which shall be exceedingly efficient in operation and comparatively economical in cost.

In my improvement I employ a compression chamber arranged to be placed at properly timed intervals in communication with an explosion chamber in which the power is produced for operating the crank shaft of the engine for power purposes.

In the drawing I have illustrated an engine having two explosion chambers and two compression chambers, the compression chambers being arranged in suitable operative relation with the respective explosion chambers. Between each explosion chamber and its companion compression chamber, is located a valve which controls the passage of explosive mixture from the manifold or conduit located between the carburetor and the engine proper, to the compression chamber while communication is cut off between the compression chamber and the explosion chamber. Again after the charge of explosive mixture is drawn into the compression chamber, this valve is actuated to open communication between the compression chamber and the explosion chamber and this occurs during the downward or inward movement of the explosion chamber piston, and after the explosion takes place, the explosion chamber being scavenged of the burnt gases or products of combustion during the filling of the explosion chamber with explosive mixture, the exhaust port of the explosion chamber being closed just before the explosive mixture reaches said port, after which the explosion chamber piston in cooperation with the compression chamber pis-

ton serves to compress the explosive mixture until the piston of the explosion chamber reaches its outward limit of movement. At this time the explosion occurs and the operation heretofore outlined is repeated. Where two explosion chambers and their companion compression chambers are employed, the explosion chamber pistons are connected with the crank shaft in opposing relation in order to produce a balancing result, the two explosion chambers and their coöperating compression chambers performing their corresponding functions alternately. As illustrated in the drawing each throttle valve is controlled by a cam and an opposing spring.

Having briefly outlined my improved construction I will proceed to describe the same in detail, reference being made to the accompanying drawing, in which is illustrated an embodiment thereof.

In this drawing, —Figure 1 is a central vertical section taken through my improved engine cutting the explosion and compression cylinders in a longitudinal direction. Figs. 2 and 3 are sections taken on the lines 2—2 and 3—3 respectively of Fig. 1. Fig. 4 is a detail view of one of the throttle valves employed in connection with the engine mechanism. Fig. 5 is a fragmentary view of the construction shown in Fig. 1. In this figure the right hand portion of Fig. 1 is illustrated but the pistons and valve are shown in different relative positions. Fig. 6 is a diagrammatic view which may be advantageously employed in describing the operation of the mechanism.

The same reference characters indicate the same parts in all the views.

Let the numeral 5 designate the crank case of my improved engine; 6 the explosion cylinders; 8 and 9 the compression cylinders and 10 and 12 the chambers which the throttle valves 13 and 14 occupy. Pistons 15 and 16 reciprocate in the explosion cylinders and are respectively connected with the crank shaft 17 by means of pitmen 18 and 19. Pistons 20 and 21 are located in the compression cylinders and are connected by means of pitmen 22 and 23 with the crank shaft. The explosion cylinders are respectively provided with exhaust ports 24 and 25. Each valve 13 and 14 is hollow and provided with a port 26 which is in communication with the manifold 27 of the en-

gine whereby the explosive mixture, during the operation of the engine is supplied through the medium of these valves. Each valve is provided near its upper extremity with a second port 28 which at properly timed intervals is brought into communication with a port 29 which connects each valve chamber with the chamber of the adjacent compression cylinder. Furthermore 10 the upper extremity of each valve chamber is connected by means of a port 30 with the corresponding extremity of the adjacent explosion chamber. Each throttle valve is provided at its upper extremity with a reduced neck 31 which is surrounded by a split ring 32 which is held in place by means of a pin 4 which passes through registering openings formed in the ring and the neck of the valve. This ring constitutes a packing 20 for the upper extremity of the valve, being the part thereof which controls the adjacent ports. The valve is closed at the top by a cap 33 which is held in place by a screw 34 or other suitable fastening means. 25 Each valve 13 and 14 is connected as shown at 35 with a rod 36 which passes through a stationary guide 37, its extremity remote from the valve being equipped with an anti-frictional device as a roller 38 which 30 engages the outer edge or peripheral face of a cam 39 which is fast on the crank shaft and so shaped, in co-operation with a spring 40, as to properly manipulate the throttle valve as heretofore outlined. This spring 35 surrounds the rod 36, one extremity of the spring bearing against the bottom 41 of the valve casing, while its opposite extremity engages a stop 42 adjustably mounted on the rod which is threaded as shown at 43 40 for the purpose, the stop constituting a nut and fashioned as shown at 44 in order that a wrench may be utilized for its adjustment. Each explosion cylinder is provided with a spark plug 45 connected in the usual manner with a source of electricity (not shown) 45 by means of conductors inclosed in a cable 46.

From the foregoing description the operation of my improved engine will be readily 50 understood.

If it be assumed that the parts of the mechanism are in the relative positions shown in Fig. 1, the piston 21 of the compression cylinder 9, is moving downwardly 55 and drawing in a charge of gas or explosive mixture from the manifold by way of the port 26 of the valve and a similar port 56 formed in the valve chamber and in communication with the conduit 27 or discharge 60 extremity of the manifold. This explosive mixture will continue to enter the compression cylinder 9, until the piston 21 of the latter has reached its downward limit of movement, and until after it has commenced 65 the return or outward stroke. During this

operation of drawing explosive mixture into the compression cylinder, the roller extremity of the rod or valve stem 36, is in engagement with the face of the cam 39, between the points 50 and 51, being the upper portion 70 of the cam when in the position shown in Fig. 2. During this operation of the piston 21, the piston 16 of the companion explosion cylinder 6, is moving downwardly 75 or in the direction of the arrow *a*, in response to an explosion which has occurred in the outer extremity of this cylinder. Hence the piston 21 during the operation of drawing explosive mixture into its cylinder 9, travels a portion of the time in the 80 same direction as the piston 16 of the companion explosion cylinder. The piston 21 however travels in advance of the piston 16, about 70 degrees. Shortly after the piston 21 begins its return stroke and before the piston 16 has completed its inward or explosion stroke, the throttle valve 14 will be moved to the position of the valve 13 in Fig. 5, whereby communication will 85 be established between the outer extremity 90 of the cylinder 9 and the corresponding extremity of the companion explosion cylinder 6, whereby the explosive mixture will be forced from the compression cylinder into the outer extremity of the explosion 95 cylinder. This explosive mixture scavenges the explosion chamber of the burnt gases or products of combustion resulting from the last explosion, these products of combustion being driven inwardly in the explosion 100 chamber and forced out of the exhaust port 25, this port being uncovered by the piston 16 just long enough to allow the burned gases to pass out, after which it is again covered by the return movement of the piston 16 which compresses the explosive mixture 105 in the upper or outer part of the explosion chamber, the valve 14 being moved to the position of the valve 13 in the right of Fig. 1, after the charge of explosive mixture has 110 been delivered to the explosion cylinder through the medium of the piston 21 of the compression cylinder 9. The final compression then takes place within the explosion chamber due to the completion of the outward stroke of the piston 16. The explosion then takes place and the operation heretofore described is repeated. That is to say the valve 14 is moved by the cam 39 to its outward limit of movement or that 115 shown at the left of Fig. 1, whereby communication is cut off between the compression cylinder and explosive cylinder and communication opened between the compression cylinder and the manifold for the reception of another charge of explosive mixture. 120

In the description heretofore given of the operation, special reference has been made to the operation of the left hand half of 130

the construction shown in Fig. 1. It may be stated that the operation of the construction of the right hand half is substantially identical, the corresponding steps of the 5 operation of the two units of the structure, taking place alternately as heretofore indicated.

- The operation of the structure may perhaps be best understood by reference to Fig. 10 6 in which the operation is diagrammed. The pointers 60 and 61 which rotate from a center 62, may be said to represent the pistons 16 and 21 of the explosion and compression cylinders respectively. Hence as 15 the pointer 60 moves from the point A to the point C in the direction of the arrow c, the piston 15 of the explosion cylinder 6, moves from its outward to its inward limit of movement, and commences the return 20 stroke, the movement from the point D to the point C indicating the return or outward movement until the exhaust port 24 is covered and the exhaust of the burnt gases completed. Then as the pointer 60 moves 25 from the point C to the point A, the piston 16 (see Fig. 5) completes its outward or compression stroke, immediately after which the explosion takes place and the operation of the piston just described is completed.
- 30 The space between the two pointers 60 and 61 may be considered the distance which the piston 21 is ahead of the piston 16 during the operation of the engine. While the pointer 61 moves from the point A to the 35 point E, the piston 21 has commenced its inward or downward stroke and during this portion of the movement of said piston the port 29 remains closed and a partial vacuum is formed in the outer extremity of the compression cylinder. The port 30 is then opened and the explosive mixture is drawn into the cylinder 13, during the time that the pointer 61 is traveling to the point C. During this time the piston 21 has 40 commenced its return stroke and the distance of the return travel is represented by the distance between the points D and C. It is estimated that there will still be a sufficient vacuum condition in the compression cylinder to cause the continued flow of explosive mixture from the manifold into the compression cylinder, until the piston 21 has made the part of its return stroke indicated by the distance from the point D to the 45 point C. Then the corresponding throttle valve will remain in the position shown at the right of Fig. 1 or whereby communication is cut off between the compression and explosion cylinders, during the time that 50 the compression piston 21 is traveling the portion of its stroke indicated by the distance between the points C and F, and during this time the explosive mixture within the compression cylinder will be compressed.
- 55 The throttle valve 13 will then move to the

position shown in Fig. 5 whereby communication between the compression and explosion cylinders is opened, and the passage of explosive mixture from the compression to the explosion cylinder takes place during 70 the balance of the outward stroke of the piston 21, or during the portion of the stroke indicated by the distance between the points F and A.

Each explosion chamber is provided with 75 a number of pins 53 arranged in front of the port 30 leading from the valve chamber to the explosion chamber, whose function is the breaking up of the explosive mixture as it enters the explosion chamber from the 80 compression chamber by way of the valve chamber (see Fig. 5).

The upper extremity of each valve chamber 10 and 12 is provided with a port from which a passage 52 leads to the upper extremity of the adjacent compression chamber, in order to allow any gas or explosive mixture to escape from the top of the valve chamber which may be trapped therein after the upper extremity of the throttle 90 valve 13 or 14 as the case may be, has passed the port 29 or 30 in its upward travel.

Having thus described my invention, what I claim is,

1. An internal combustion engine comprising an explosion cylinder, a compression cylinder, pistons therein, and a hollow valve mounted to reciprocate, the chamber in which the valve moves being in communication with the chambers of both cylinders 95 by suitable ports, the said valve having but two ports one of which establishes communication between the hollow of the valve and the manifold of the engine while the other port is adapted to register with the port 100 forming communication between the chamber of the compression cylinder and the chamber in which the valve moves.

2. An internal combustion engine comprising an explosion cylinder, a compression 110 cylinder, pistons therein, a valve chamber, a hollow valve mounted to reciprocate therein, the valve chamber being in communication with the chambers of both cylinders by way of suitable ports, the said valve having 115 but two ports one of which establishes communication between the hollow of the valve and the manifold of the engine while the other port is adapted to register with the port forming communication between the 120 compression cylinder chamber and the valve chamber, and means for actuating the valve to place, first, its interior chamber or hollow in communication with the compression cylinder, second, its exterior chamber 125 in communication with the chambers of both cylinders, and third, to cut off both cylinder chambers from communication with the exterior valve chamber.

3. An internal combustion engine com-

- prising an explosion cylinder, a compression cylinder, pistons therein, a valve having an interior chamber, an exterior chamber in which the valve is mounted to reciprocate, 5 the exterior chamber being in communication with the chambers of both cylinders by suitable ports, the said valve having but two ports one of which establishes communication between the hollow of the valve and the 10 manifold of the engine while the other port is adapted to register with the port forming communication between the compression cylinder chamber and the exterior valve chamber, and means for actuating the valve 15 to place its interior chamber in communication with the compression cylinder chamber; its exterior chamber in communication with the chambers of both cylinders; and to cut off the compression chamber from communication with the interior chamber of the valve; the three aforesaid conditions occurring successively and the series of conditions being repeated constantly during the operation of the engine. 20
- 25 4. In an internal combustion engine, the combination with a manifold in communication with a source of explosive mixture, of an explosion cylinder, a compression cylinder and an interposed valve chamber having 30 three ports forming communication respectively with the manifold, the explosion cylinder chamber and the compression cylinder chamber, and a hollow valve movable in said valve chamber, and having two ports only 35 by way of which the hollow of the valve is constantly in communication with the manifold and alternately in communication with the compression cylinder chamber.
5. In an internal combustion engine, the 40 combination with a manifold in communication with a source of explosive mixture, of an explosion cylinder, a compression cylinder and an interposed valve chamber having three ports forming communication respectively with the manifold, the explosion cylinder chamber and the compression cylinder chamber; and a hollow valve movable in said valve chamber and having two ports only adapted to register with the ports of 45 the valve chamber which communicate respectively with the manifold and the compression cylinder chamber. 50
- 55 6. In an internal combustion engine, the combination with a manifold in communication with a source of explosive mixture,
- of an explosion cylinder, a compression cylinder and an interposed valve chamber having three ports forming communication respectively with the manifold, the explosion cylinder chamber and the compression cylinder chamber, and a hollow valve movable in said valve chamber, and whose interior chamber is adapted to be in communication with the manifold and the compression cylinder chamber, but is always cut off from the chamber of the explosion cylinder. 60
7. In an internal combustion engine, the combination with a manifold in communication with a source of explosive mixture, of an explosion cylinder, a compression cylinder and an interposed valve chamber having three ports forming communication respectively with the manifold, the explosion cylinder chamber and the compression cylinder chamber, and a hollow cylindrical valve movable in said valve chamber and whose interior chamber is constantly in communication with the manifold, alternately in communication with the compression cylinder chamber, and never in communication with the chamber of the explosion cylinder. 70
8. In an internal combustion engine, the combination with a manifold in communication with a source of explosive mixture, of an explosion cylinder, a compression cylinder and an interposed valve chamber having three ports forming communication respectively with the manifold, the explosion cylinder chamber and the compression cylinder chamber, the said ports which communicate with the chambers of the two cylinders being arranged substantially in the same plane, and a hollow valve movable in said valve chamber and whose interior chamber is adapted to be in communication with the manifold and the compression cylinder chamber but is always cut off from the chamber of the explosion cylinder, the movement of the valve being such as to control the passage of explosive mixture through the valve chamber from the chamber of the compression cylinder to the chamber of the explosion cylinder. 85
- 90 In testimony whereof I affix my signature in presence of two witnesses. 95
